UNITED STATES PATENT OFFICE.

CHRISTINA LINBORG, OF GALETON, PENNSYLVANIA.

GUIDING AND MARKING DEVICE FOR SEWING-MACHINES.

No. 874,777.

Specification of Letters Patent.

Patented Dec. 24, 1907.

Application filed August 8, 1907. Serial No. 387,672.

To all whom it may concern:

Be it known that I, CHRISTINA LINBORG, a citizen of the United States, residing at Galeton, in the county of Potter and State of Pennsylvania, have invented certain new and useful Improvements in Guiding and Marking Devices for Sewing-Machines, and do declare the following to be a full, clear, and exact description of the invention, such as will enable others skilled in the art to which it appertains to make and use the same.

This invention relates to improvements in adjustable guiding and marking attachments for sewing machines.

15 The object of the invention is to provide a guiding and marking attachment of this character which may be quickly and easily attached to a sewing machine to guide the rows of stitches and to mark a parallel line 20 for the next row of stitching, whereby the hems, seams, tucks, or plaits, may be conveniently formed, or braid or trimming sewed on in even, parallel rows, means being provided whereby the guide may be adjusted to mark 25 guide lines at various distances apart.

With this object in view, the invention consists of certain novel features of construction, combination and arrangements of parts as will be more fully described and particularly pointed out in the appended claims.

In the accompanying drawing, Figure 1 is a perspective view of the device showing the same attached to the presser foot bar of a sewing machine; Fig. 2 is an enlarged front 35 view of the attachment partly in section; and Fig. 3 is an end elevation of one end of the same.

Referring more particularly to the drawings, 1 denotes the attachment, which comprises a pair of adjustably connected supporting bars, 2, which are adjustably held together by means of an apertured bolt, 3, through the aperture in which said rods are passed. On the bolt, 3, is arranged an 45 attaching clip, 4, in the bolt-engaging portion of which are formed aligned apertures 5, which coincide with the aperture in the bolt and through which the bars or rods, 2, also project. The bolt, 3, is provided with a reduced threaded extension on which is adapted to be screwed a clamping nut, 6, which, when screwed up on the threaded end of the bolt, will draw the rods or bars 2 into tight engagement with the walls of the apertures, 5, thereby securely clamping or holding the same in their adjusted positions. The clip,

4, is provided with curved plates, 7, which are adapted to embrace the presser foot bar of the machine, and in one of the plates 7 is formed a threaded aperture in which is arranged a clamping screw, 8, on the inner end of which is swiveled a curved clamping plate, 9, which, when the screw 8 is screwed inwardly, is adapted to clamp against the side of the presser foot bar and thus securely hold 65 the attachment in place thereon.

One end of each of the bars is reduced to form a shoulder, 10, and on said reduced ends of the bars are arranged standards, 12, of parallel guide feet, 13. The standards 12 are 70 clamped in position against the shoulders 10 of the bars, 2, by means of thumb nuts, 14, which are adapted to be screwed onto the reduced threaded ends of the bars, as shown.

Adapted to be detachably engaged with 75 the standards 12 of the guide feet is a chalk holder 15, in the outer end of which is formed a tapered chalk receiving socket, 16. On the outer end of the holder 15 is formed a spring clamping plate, 17, by means of which 80 the holder is secured to either of the supports, 12. The rods of bars 2, are provided with a scale of measurements, whereby accurate adjustments of the same may be made.

In the operation of the device, the clip, 4, 85 is secured to the presser foot bar of the machine, as hereinbefore described, and after which the bars, 2, are adjusted to bring the marking feet 13 to the desired position with respect to the seam or row of stitching which 90 is being made by the machine, after which the clamping nut, 6, is tightened up to hold the bars in their adjusted position. The chalk holder is now applied to the proper guide foot standard so that as the row of 95 stitching is made by the machine, a chalk line will be drawn parallel therewith, and at the desired distance therefrom, thus marking the place for the next row of stitching, as will be readily understood. 100

Having thus fully described my invention, what I claim as new and desire to secure by Letters-Patent, is:

1. A guiding and marking attachment for 105 sewing machines comprising a pair of adjustably connected supporting bars, having arranged thereon a scale of measurements, means to secure said bars to the presser foot bar of the machine, guide feet removably secured to the opposite end of said supporting bars, a chalk holder, and a spring clamp on said holder whereby the same is detachably 110

secured to either of said guide feet, substantially as described.

2. A guiding and marking attachment for sewing machines comprising a pair of adjustably connected supporting bars having arranged thereon a scale of measurements, a fastening bolt having formed therein a transversely disposed passage to receive said bars, a fastening clip having an apertured bolt envelope 5
10 gaging portion through which said bars are adapted to project, a clamping nut adapted to be screwed onto the threaded end of said bolt, whereby the supporting bars are rigidly held together in their adjusted positions, 15 guide feet standards adapted to be secured upon the outer end of said supporting bars, guide feet on the lower ends of said standards, and a chalk holder adapted to be secured to said standards, substantially as described.

3. A guiding and marking attachment for sewing machines, comprising a pair of adjustably connected supporting bars adapted

to be lengthened or shortened to adjust the device, a fastening clip adapted to be engaged with the presser foot bar of a machine, a clamping screw arranged in said clip, a clamping plate swiveled on the inner end of said screw and adapted to be engaged thereby with the presser foot bar, reduced 25 threaded ends formed on said bars to provide shoulders, guide feet supports adapted to be engaged with said reduced threaded ends, clamping nuts adapted to be screwed onto said ends to hold said standards in engagement with said shoulder, and guide feet formed on the lower end of said standards, 30 substantially as described.

In testimony whereof I have hereunto set my hand in presence of two subscribing witnesses.

CHRISTINA LINBORG.
